(57) **CLAIM**

The ornamental design for a motorcycle rear lighting accessory, as shown and described.

DESCRIPTION

FIG. 1 is a perspective view of the motorcycle rear lighting accessory.

FIG. 2 is a front elevation view thereof.

FIG. 3 is a rear elevation view thereof.

FIG. 4 is a top side view thereof.

FIG. 5 is a bottom side view thereof.

FIG. 6 is a right side view thereof; and,

FIG. 7 is a left side view thereof.

The front surface portions and rear surface portions shown in broken lines form no part of the claimed design.
